UNITED STATES PATENT OFFICE.

ERNEST F. SANTO, OF WALLA WALLA, WASHINGTON.

STABILIZER FOR FLYING MACHINES.

Application filed August 30, 1926. Serial No. 132,462.

This invention relates to stabilizers for heavier than air flying machines, and has as one of its objects to provide a stabilizer that is readily available for operation.

5 Another object of this invention is to provide a stabilizer that will be carried on a flying machine and that may be depended upon to support the machine when necessary.

10 A further object of this invention is to provide a stabilizer that may be restored to a position of rest while in the air.

A further object of this invention is to provide a stabilizer and providing a means 15 for filling or emptying said stabilizer of gas.

With these and other objects in view, reference is now had to the accompanying drawings in which

Fig. 1 is a perspective view of a fragment 20 of the body of a flying machine with part broken away showing the gas plant and controls;

Fig. 2 is a perspective view of a guide yoke;

25 Fig. 3 is a side elevation of a flying machine showing the stabilizer in the operative position;

Fig. 4 is a side view of the stabilizer partly folded;

30 Fig. 5 is a plan view of a fragment of a wing showing the stabilizer at rest in a compartment provided for the purpose;

Fig. 6 is a plan view of means for drawing the stabilizer to rest and for releasing 35 it for operation; and

Fig. 7 is a cross sectional view of the flexible casing.

Having reference to the drawings, like numerals refer to like parts throughout the 40 several views, and the numeral 1 refers to a heavier than air flying machine which may be of any type, and attached to the flying machine, in a manner to be explained, is a gas bag 2 preferably oblong, or of cigar 45 shape, and this gas bag comprises a plurality of compartments consisting preferably of an upper compartment 3 having sufficient capacity to support the weight of said bag, a lower compartment 4, and end 50 compartments 5 positioned on either side of the upper and lower compartments respectively, and in a manner that the lower compartment will act to maintain the ends of the bag outward in their proper position by its 55 pressure against the end compartments when the whole is inflated.

By this means the gas bag 2 may be foldably collapsed by deflating the end compartments then deflating the lower compartment and finally and successively deflating 60 the upper compartment when the bag is at rest.

Within the body of the flying machine, and carried thereby, is a gas supplying means 6, which may be of the usual type or 65 which may consist of a storage tank 7, a pump 8, the latter operated by a motor 9, in turn driven by a storage battery 10, a switch 11 being mounted on the instrument board 12 for the purpose of control.

The storage tank 7 is provided with a main lead 13, in which is a pressure gauge 14 mounted on the instrument board, and from this pressure gauge is arranged a pair of flexible outlets 15, each outlet having its 75 individually controlled valve 16, while a second gauge 17 is likewise connected with the main lead and mounted on the instrument board and has valves 16^a, and flexible outlets 18 and 18^a leading therefrom.

80 All four outlets are extended to form flexible leads connected with the bag and are encased in a flexible casing 19 for protection.

Two of the outlets, 18 and 18^a, are preferably connected to the compartments 3 and 85 4 respectively, while the other two outlets 15 and 15 are connected with the compartments 5.

90 A return pipe 13^a is connected between the main lead and the pump 8, and a valve 13^b is provided in the return pipe, with a second valve 13^c in the main lead, to control these two leads.

95 By this means it is obvious that by closing all of the valves excepting the valve 13^c the pressure of the tank will be registered on the gauge 14; that by closing this valve and by opening either of the valves 16 or 16^a the pressure in either of the four compartments will be registered on their respective gauges; and that by closing the valve 13^c and opening valve 13^b any of the compartments can be emptied by the pump by manipulating the valve complementary to the respective compartment.

100 This single flexible casing is now arranged over a paying-out-jack 20, and each of these flexible tubes passes to and is connected with one of the above mentioned compartments in the bag.

110 It will now be noted that by means of the above mentioned valves that any of the com-

5 compartments in said bag can be deflated at will, the result being that by deflating the end compartments 5, and then deflating the lower compartments 4, the bag will assume a position shown in Fig. 4 and be supported in the air by the upper compartment 3, which as before mentioned, has the necessary capacity to support the weight of the bag 2.

10 The paying-out-jack 20 may consist of any suitable means for taking care of the casing 19, a typical means being shown in Fig. 6, which consists of a plurality of sheaves 21, divided into two sets, each set being mounted upon its respective shafts 22, 15 with one of said shafts being fixed with respect to longitudinal movement, while the other shaft is movable longitudinally being provided on each end with a block 23 threadedly engaging a pair of worms 24, the worms 20 carrying a means for rotating them consisting of spur gears 25 intermeshed with a spur pinion 26, the latter being connected to any prime mover (not shown) by means of the shaft 27.

25 Now in a wing 28, or other suitable place about the flying machine, is provided a receptacle 29, and this receptacle is preferably positioned between the center of gravity of the flying machine and the bag, for the purpose that when the bag is drawn to the machine it will readily lodge in said receptacle.

30 For the purpose of drawing the bag into the machine cords are used, and to prevent tangling thereof, a yoke 31 is provided, having an opening 32 in its center, on both sides of which opening are rotatably mounted rollers 33.

35 This yoke 31 is supported from the bag by four or more cords 34, in such manner that the yoke remains at a fixed distance from the top compartment to which it is secured.

40 Now supporting cords 35 are attached to the end compartments 5 of said bag, and these cords pass through the yoke 31 over the rollers 33 and join together to form a single cord 36, that likewise passes over the sheaves of the paying-out-jack 20 in a 45 manner to be operated coincident with said flexible casing 19.

45 By this means the casing and the single supporting cord 36 are maintained in close proximity, both in drawing the bag to the machine after deflation, or in permitting it to rise therefrom after inflation, and by this means tangling of the cord and casing is positively prevented, the cord and casing being under tension at all times.

50 Now by positioning the receptacle so that the line of the cord and casing, when the balloon is inflated, will extend to the forward end of the receptacle, it is obvious that with the compartments successively deflated that 55 the bag will come to rest in the receptacle

and in the compact manner shown in Fig. 5.

55 In use the bag is presumed to rest in the receptacle and if desired a suitable cover (not shown) may be provided to cover said receptacle.

70 The flying machine now ascends and through some accident the machine is rendered inoperative. To stabilize the machine and prevent accident the proper valves are opened and the switch thrown, when the 75 gas will proceed to inflate the upper compartment of the bag until it raises the bag from the receptacle, augmented by the inflation of the lower compartment, and finally the end compartments are inflated and the 80 bag is now in condition to stabilize and support the flying machine in the air with perfect safety.

85 Now in this case the gas may be drawn from the storage tank 7, without the assistance of the pump, or if for any reason sufficient gas is not available in the tank to completely inflate the bag a small gas making machine 37 may be provided, which gas machine is connected to the pump 8, valves 38 90 being placed adjacent to the pump and in the pipe line 13^a, to regulate the flow of gas therethrough, whereby sufficient gas may become available, the gas in this case being pumped through the storage tank.

95 The pump will now operate to compress the gas in the storage tank, to fill the compartments of the bag, or to draw the gas from the gas machine to distribute it either to the bag or to the storage tank.

100 In deflating the bag the reverse operation obtains and by manipulating the valves on the instrument board the end compartments are deflated. The bag now uniformly collapses, the ends being drawn toward the 105 yoke by the supporting cords, and finally by operating the paying-out-jack the bag is drawn to its receptacle, when final deflation of the upper compartment takes place and the bag rests compactly folded in said receptacle.

110 Having thus described my invention, I claim:

115 In a stabilizer, a flying machine, a collapsible gas bag comprising a plurality of compartments, said compartments consisting of upper and lower compartments, and end compartments, a gas supplying means carried by said flying machine and provided with means to inflate or deflate said compartments successively, a receptacle provided in said flying machine, a yoke supported by 120 said bag, supporting cords attached to said bag and said flying machine and passed through said yoke, and arranged to uniformly collapse said bag and to draw said bag into said receptacle.

125 In testimony whereof I affix my signature.

ERNEST F. SANTO.
